United States Patent Office.

ALBERT F. ALLEN, OF PROVIDENCE, RHODE ISLAND.

Letters Patent No. 76,579, dated April 14, 1868.

IMPROVEMENT IN HOSE-COUPING WRENCH.

The Schedule referred to in these Letters Patent and making part of the same.

TO ALL WHOM IT MAY CONCERN:

Be it known that I, ALBERT F. ALLEN, of the city and county of Providence, and State of Rhode Island, have invented a new and improved Signal Hose-Wrench for Coupling and Uncoupling Engine-Hose; and I do hereby declare that the following is a full, clear, and exact description of the same, reference being had to the accompanying drawings, making part of this specification, in which—

Figure 1 is a view of my improved hose-wrench applied to a hose-coupling in the way of its use.

Figure 2 is another view edgewise, longitudinally, of the same.

Similar letters indicate like parts in all the figures.

The invention herein described is designed more especially to operate and carry into full effect the principle of action and the purposes of the improved hose-coupling patented by me, September 3, 1867, for stopping the flow of water towards the nozzle or discharging-point, and of starting the flow of water again instantly, at will.

In addition to the purposes and uses of said coupling set forth in the specification attached to the said patent of September 3, 1867, I have discovered by practice that the stream or body of water that passes from the engine or pump to the nozzle from which it is discharged, may be employed as a means of communicating orders or directions from the engineer who has charge of the engine or like apparatus, to those having charge of the hose-pipe at the other end of the line of hose connected with such engine, or *vice versa*, by quickly or instantly stopping or starting the flow of water, once, twice, or thrice, or any given number of times, such stopping and starting of the water being signals corresponding with those of the electric or magnetic current in telegraphing, and, when understood and agreed upon, will, in its way, subserve all the purposes of telegraphic communication between the engine and the hose-pipe or nozzle, and those having charge of either; and although the coupling, as described in the said specification, is fully complete and perfect in itself to accomplish this desirable purpose, it is found that the ordinary hose-wrench, which partly spans and hooks upon one of the horns of the coupling, is entirely unsuited to the purpose of instantly turning the "sleeve" of said coupling in either direction, to stop and start the flow of water with that marked effect as to answer the purpose of a signal, for the reason that the position of the ordinary hooked wrench has to be reversed at each stopping and starting produced by turning said "sleeve," and that this reversing of the position and hold of the wrench cannot be done with that degree of promptness and precision to constitute an effective signal. I have therefore invented a different construction of hose-wrench, by which the instant turning of the "sleeve" may be accomplished, without changing or removing it from its position, to stop or start the flow of water in the manner and for the purposes contemplated, and which is at the same time simple, and equally applicable and useful for the ordinary form of couplings for engine-hose, &c.

My invention consists in so constructing the hose-wrench with a socket to receive one of the horns or projections on the coupling, and with suitable horns or projections extending each way from the said socket, so as to span the outside circumference of the coupling, that by means of a handle extending from said socket, the coupling or the sleeve of the coupling may be instantly turned in either direction without removing or changing the position of the wrench.

In the drawings, G is the coupling, having horns D D, as shown, and F is the socket of the wrench, which receives one of the horns of said coupling, as shown in dotted lines. H is the handle, in line with the centre of the socket F, and B B are the horns of the wrench, projecting upon each side of the socket, and spanning one half of the circumference of the coupling. Thus constructed, it will be seen that the said wrench is a lever, of which either of the horns B B, according to the direction in which the coupling or its "sleeve" is to be turned, is the fulcrum, the socket is the point of resistance, and the handle H is the point where the power is applied to overcome such resistance, and that the effect and force is exerted equally in turning in either direction without removing the wrench from the coupling, and therefore the "sleeve" of my improved patented coupling may be instantly turned, first in one direction and then in the other, to open and close the passages at which the water

from the hose escapes, and with such promptness as to be immediately perceptible at both ends of the line of hose, and to serve all purposes of a definite signal to those in charge at either end.

What I claim, and desire to secure by Letters Patent, is—

The signal-hose wrench, constructed substantially as herein described, with a socket, D, the spanning-horns B, and handle H, for the purposes set forth.

ALBERT F. ALLEN.
